UNITED STATES PATENT OFFICE.

JAMES S. BREED, OF HOUSTON, TEXAS.

LINEMAN'S WRENCH.

Application filed June 28, 1926, Serial No. 119,006. Renewed December 31, 1927.

My invention relates to an improved wrench for use by linemen in the operations of setting up telephone or telegraph poles, adjusting them in place, and also in securing the cross arms upon the poles.

In the different operations connected with the fixing of a cross arm upon the poles and bracing them in position, and also in the operation of connecting the guy wires to the pole, a wrench is necessary which is adapted to receive several different sizes of nuts and also adapted to fit in certain places wherein the monkey wrench is usually required. It is inconvenient for linemen to carry more than one wrench for engaging all of the different nuts which have to be tightened in securing the parts in position, as described.

It is an object of my invention to provide a combination wrench having means thereon to engage a number of different sizes of nut and also adapted to fit into the different positions where the wrench has to be used. It is also desired to provide means whereby the socket openings formed in this wrench may be employed in tightening a nut over the end of a bolt for a material distance, as is usually necessary. The invention resides in the particular construction and arrangement of the nut receiving openings in the tool.

Referring to the drawing herewith, Fig. 1 is a perspective elevation of a wrench embodying my invention. Fig. 2 is a similar elevation taken from the side opposite the side shown in Fig. 1. Fig. 3 is a transverse section on the plane 3-3 of Fig. 1. Like numerals of references are employed to designate like parts in all the views.

In constructing the wrench, I provide a handle member 1 which is preferably flattened so that it is wider than it is thick, and as light as may be consistent with proper strength. On one end of the handle is formed a head 2. Laterally projecting sockets 3 and 4 are formed in this head, the comparative sizes of which are indicated best in Fig. 3. The sockets are squared to receive the nuts which are ordinarily employed upon bolts connecting together the cross arms on the telephone pole and also in engaging upon the clamping plates which are used in clamping the guy wires together when adjusted. In this operation the nut has to be tightened on to the bolt for a material distance so that the end of the bolt projects through the nut, and in

order to accommodate the bolt, the two sockets 3 and 4 are connected transversely through the head of the wrench with a cylindrical passage 5. This allows the bolt to extend through the socket from either side when the nut is screwed upon the bolt.

On one side of the head approximately in axial position, I cut a nut receiving notch or recess 6. This recess is cut from the forward end inwardly so as to connect with the central passage 5, and in order to straighten this opening, the head is provided with two forwardly extending arms 7, the full thickness of the wrench head. This opening is for engaging with the nuts employed on the bolts which space wire supporting arms upon the pole. It is necessary to get between the two adjacent arms and an ordinary socket wrench cannot do this.

Upon the opposite side of the wrench head and connecting with the recess 6 is a smaller nut-engaging opening 8 adapted to receive the nuts of a smaller diameter frequently employed upon the cross arms.

At the opposite end of the handle is a smaller head 9 which has nut receiving openings on each side thereof, one indicated at 10 being slightly larger than the opening 11 in the opposite side.

In the wrench thus formed all of the nuts which are to be screwed up in connection with the lineman's work are provided for. It will be noted that there are two sizes of openings in the head 9, and four sizes of openings in the head 2. I have provided two socket wrenches 3 and 4 and two other nut receiving openings 6 and 8. In forming the side of the head opposite to that within which the nut receiving recess 6 is formed, I have shown the head as being cut down at 12 so as to take away some of the unnecessary weight in the head, and also connecting centrally thereof, as shown at 13 in Fig. 3 with the central channel 5 through the head. This as shown in Fig. 4 leaves a lateral opening which may be engaged on the end of an iron strap or brace such as is usually employed in bracing the cross arms to the body of the pole. It is found to be usually necessary to bend the brace rods to fit the pole or the cross arm and this opening 13 fits the end of the brace so that it may be engaged and twisted to the extent necessary to make it fit against the side of the pole. This is a device frequently used in the lineman's work.

The advantages of the tool will be obvious to one skilled in the art. The wrench may be fitted within the belt of the lineman and this one tool will serve the purpose of performing all the operations in screwing up nuts and fixing the braces upon the cross arms, as will be required.

Having thus described my invention, what I claim as new and desire to protect by Letters Patent is:

1. A lineman's wrench including a handle, a head thereon having opposite sockets at each side of said head and a passage connecting said sockets, said head having a nut receiving recess formed in one side of

said head axially thereof to connect with said passage, in the manner described.

2. A lineman's wrench including a handle, a head on one end thereof having sockets formed therein and a passage connecting said sockets, said head having a nut receiving recess on one side thereof axially of said handle, the opposite side of said head being cut away to connect with said passage to form a brace receiving opening, for the purpose described.

In testimony whereof I hereunto affix my signature this 23rd day of June, A. D. 1926.

JAMES S. BREED.
